United States Patent Office.

R. A. WEBSTER, OF SANDISFIELD, ASSIGNOR TO HIMSELF, JOHN DOWD,
AND R. J. DOWD, OF LEE, MASSACHUSETTS.

Letters Patent No. 79,090, dated June 23, 1868.

IMPROVEMENT IN INNER SOLES FOR BOOTS AND SHOES.

The Schedule referred to in these Letters Patent and making part of the same.

TO ALL WHOM IT MAY CONCERN:

Be it known that I, R. A. WEBSTER, of Sandisfield, in the county of Berkshire, and State of Massachusetts, have invented a new and useful Improvement in Inner Soles for Shoes and Boots; and I do hereby declare that the following is a full, clear, and exact description thereof, which will enable those skilled in the art to make and use the same, reference being had to the accompanying drawings, forming part of this specification.

This invention relates to a new and useful improvement in inner soles for boots and shoes, whereby such boots and shoes are rendered impervious to water, and soft and pleasant to the wearer.

And it consists more particularly in additions to an inner sole, for which Letters Patent were granted me, dated February 18, 1868.

The drawing represents a longitudinal side view of an inner sole constructed according to my invention. Figure 2 is an edge view of the same.

Similar letters of reference indicate corresponding parts.

The inner sole, for which I have already obtained Letters Patent, is composed of a piece of wood-veneer and a piece of felting or cloth, of either cotton or wool, between which is a thin layer of gutta percha or India rubber.

My improvement consists in adding thereto another piece of gutta percha or rubber and another piece of cloth or paper, thereby greatly strengthening the same, and adding much to its durability and usefulness.

In the drawing, A represents the improved inner sole.

B is a layer of cloth.

C is a layer of gutta percha or India rubber.

D is wood-veneer.

E (covering the wood) is another layer of gutta percha or rubber.

F is a layer of cloth, of any suitable kind, or paper, thus forming five layers, which are firmly cemented together, making an elastic, durable, and entirely water-proof sole, soft and easy to the foot, while it is very thin and light.

I claim as new, and desire to secure by Letters Patent—

The inner sole A, constructed substantially as described, for the purposes set forth.
